CLAIM

The ornamental design for a pulley, shaft and blade-holder assembly for a power-driven lawnmower or the like, substantially as shown.

DESCRIPTION

FIG. 1 is a side elevational view of a pulley, shaft and blade-holder assembly for a power-driven lawnmower or the like showing our new design;

FIG. 2 is a top plan view;

FIG. 3 is a bottom plan view; and

FIG. 4 is a horizontal sectional view taken along the line 4—4 of FIG. 1.

FIG. 1.

FIG. 2.

FIG. 3.

FIG. 4.
